Attorney

UNITED STATES PATENT OFFICE.

WALTER B. JOHNSON, OF BRECKENRIDGE, TEXAS.

SHOE-SHINING CABINET.

Application filed November 6, 1925. Serial No. 67,232.

This invention relates to new and useful improvements in shoe shining cabinets and particularly has to do with shoe shining equipment for home use.

5 An object of the invention is to provide a shoe shining cabinet preferably in the form of a box or container that is simple in construction, neat and compact in design as well as being easy to handle and transport.

10 Another object of the invention is to provide a shoe shining cabinet having a revolvable top that when inverted from its normal position will expose a foot rest upon which the shoe to be shined may be rested.

15 A construction designed to carry out the invention will be hereinafter described together with other features of the invention.

The invention will be more readily understood from a reading of the following specification and by reference to the accompanying drawings, in which an example of the invention is shown, and wherein:

Fig. 1 is a front elevation of a shoe shining cabinet constructed in accordance with 25 my invention,

Fig. 2 is an end view of the same,

Fig. 3 is a similar view to Fig. 1 showing the front side opened and the top inverted,

Fig. 4 is an end view of the same,

30 Fig. 5 is a plan view of Fig. 1,

Fig. 6 is an enlarged cross-sectional view taken on the line 6—6 of Fig. 4, showing the special holding means of the shoe paste box,

35 Fig. 7 is an enlarged cross-sectional view taken on the line 7—7 of Fig. 5 showing a keeper and screw engaged (normal position),

Fig. 8 is a detail of the same,

40 Fig. 9 is an enlarged sectional view of a latch and screw engaged (operative position), and

Fig. 10 is a detail of the same.

In the drawings the numeral 10 designates a box, and consists of a bottom 11 having 45 ends 12 and a back 13. A front member 14 is hinged to the bottom member and is arranged to be swung downward as is shown in Figs. 3 and 4 thereby giving access to the box where the shoe shining supplies are to be kept.

50 A revolvable top member is centrally pivoted at each end to the end members 12 by any suitable means such as countersunk screws 16. For holding the front member 14 upright and also for holding the top

member 15 on a horizontal plane round headed screws 17 are provided in the front edge of said top member and are adapted to engage in depending loop shaped keepers 18 which are countersunk in recesses 19 provided in the upper edge of the front member 14, (normal position).

For holding the top in its operative position, resilient metal latches 20 are countersunk in recesses 21 which are provided in 65 the upper edge of the back member 13 and are disengaged in normal position.

A partition 22 is provided within the box to afford separate compartments to receive the different necessities of a shoe shining outfit, such as brushes, cloths and the like. A foot rest 23 is secured to the underside of the top member 15 and is out of sight when the box is closed. A leather strap 24 is fastened to the upper side of the top member 15 thereby affording a hand hold by which the box may be easily and quickly transported.

A novel feature of the invention resides in the shoe paste holding member 25 which is especially adapted for containing any 80 standard paste box A. The member is cup shaped and conforms snugly with the lower member B of the paste container and has an outwardly directed circumferential flange 26 which registers with the bead C of the lower member B of the paste container. A recess 27 provided in the upper portion of the holding member 26 is adapted to receive the opener D of the paste box.

In Figs. 1, 2 and 5 the box is shown in its 90 normal or inoperative position, the leather strap 25 exposed and the box is in condition to be moved about to any desired location. By pressing down upon the back portion of the top member 15, the pins 17 will slide 95 out of engagement with the loop shaped latches 18 which are mounted in the upper portion of the front member 14, thus allowing the top to be revolved and the hinged front member 14 to be swung downward as 100 shown in dotted lines in Fig. 2.

It will be seen that after the pins and latches 18 are disengaged the front member may be entirely let down and the top member inverted thereby exposing the foot rest 105 24 as is shown in Figs. 3 and 4. The inverting of the top member will cause the pins 17 which are secured to the front side of said member to frictionally engage with the spring metal latches 20 provided in the back 110

member 13, (Figs. 9 and 10) thus holding the top in its operative position (Figs. 3 and 4).

Various changes in the size and shape of the different parts as well as modifications and alterations may be made within the scope of the appended claims.

What I claim is:

1. In a shoe shining cabinet, a box comprising an invertible top centrally pivoted along its longitudinal axis, a hinged front member, an upright back member, the side edges of the top lying between the upper portions of said members, fastening means carried by one side edge of the top, and co-operating means for engagement with the fastening means carried by the front member for fastening said top and front member together.
2. In a shoe shining cabinet, a box comprising an invertible pivoted top member having pins on one side, a hinged front member having latches adapted to be engaged by said pins to hold the top and front rigid, and a back member having keepers adapted to be engaged with said pins, when said top is inverted.
3. In a shoe shining cabinet, a box having an open top and open front, a revolute top

member journaled in the top of the box and having a foot rest in its under side brought into operative position when the top member is revolved, a front member hinged to the lower edge of the open front of the box, pins on one edge of the top member, latches on the upper edge of the front member adapted to be engaged by the pins when the front member is closed, and keepers on the back wall of the box for engaging the pins when the top member is revolved and the front member is open.

4. In a shoe shining cabinet, a box comprising an invertible top centrally pivoted along its longitudinal axis, a hinged front member, an upright back member, the side edges of the top lying between the upper portions of said members, fastening means carried by one side edge of the top, co-operating means for engagement with the fastening means carried by the front member for fastening said top and front member together, and means carried by the back member adapted to be engaged by the fastening means for supporting the top in its inverted position.

In testimony whereof I affix my signature.

WALTER B. JOHNSON.
